DESIGN FOR AN OVERTSHOE

Lela Burt, Des Moines, Iowa, assignor to Mishawaka Rubber and Woolen Manufacturing Company, Mishawaka, Wis., a corporation of Indiana.

Application February 16, 1949, Serial No. 900

Term of patent 14 years

(Cl. D7—4)

To all whom it may concern:

Be it known that I, Lela Burt, a citizen of the United States, residing at Des Moines, in the county of Polk and State of Iowa, have invented a new, original, and ornamental Design for an Overtshoe, of which the following is a specification, reference being had to the accompanying drawing, forming part thereof.

Fig. 1 is a perspective view showing the side and the front of an overshoe embodying my new design; and

Fig. 2 is a view similar to Fig. 1, showing part of the shirred front turned down.

I claim:

The ornamental design for an overshoe, as shown,

LELA BURT,
